UNITED STATES PATENT OFFICE.

JACOB KAPPLER, OF PHILADELPHIA, PENNSYLVANIA, ASSIGNOR TO GILL & COMPANY, OF PHILADELPHIA, PENNSYLVANIA, A CORPORATION OF PENNSYLVANIA.

DESIGN FOR A LAMP SHADE OR REFLECTOR.

40,919.

Specification for Design.

Patented Sept. 27, 1910.

Application filed August 14, 1909. Serial No. 512,930. Term of patent 14 years.

To all whom it may concern:

Be it known that I, JACOB KAPPLER, a citizen of the United States, residing at Philadelphia, in the county of Philadelphia and State of Pennsylvania, have invented a new, original, and ornamental Design for a Lamp Shade or Reflector, of which the following is a specification, reference being had to the accompanying drawing, forming part thereof.

Figure 1 is a side view in elevation of a lamp shade or reflector showing my new design. Fig. 2 is a bottom plan view.

The shade has an external surface ornamented with reversely curved plain and beaded prisms, every fourth prism being a

beaded prism, the beads being located in a row at the line defining the two meeting surfaces of the prism and projecting from said line. All said prisms extend from the collar at the top to the lower circumferential edge of the shade, the circumferential surface adjacent the edge being crimped or inwardly and outwardly bent, as shown.

I claim:

The ornamental design for a lamp shade or reflector, as shown and described.

JACOB KAPPLER.
